SHORT RIBBED HULLER GIN

Jeffrey J. Wallace, Amite, La., assignor to Gullett
Gin Company, Amite, La., a corporation of
Louisiana

Application May 28, 1940, Serial No. 337,725

3 Claims. (Cl. 19—56)

This invention relates to huller gins of the type which have an inner ginning breast and an outer huller breast, forming between them a roll box adjacent the top and a seed duct adjacent the bottom, the front and rear walls of the seed duct being defined by sets of ribs, carried respectively by the ginning breast and huller breast, between which ribs the gin saws pass.

It is customary in gins of this type, to have the ribs on the huller breast extend continuously to such a height that the rims of the saws must pass between them in the upper quadrant of their rotation, as well as in the lower quadrant. This construction has certain disadvantages, among which is the fact that if a long lock of cotton is engaged by the saws on opposite sides of one of the huller ribs, it will be carried upward by the saws against the intervening rib and must be broken by the saws before it can be drawn through into the roll box. This causes a great deal of breaking of the cotton, particularly if it is of long staple.

Another disadvantage is that the upper ends of the ribs accumulate cotton, which if not frequently removed packs against the saws and may catch fire through friction with the saws.

One of the objects of the present invention is to have the fixed ribs of the huller breast terminate just below the rims of the saws in the upper quadrant, so that cotton locks engaged by adjacent saws can be carried over into the roll box without being broken, and to provide a series of rotary elements adjacent the ends of the ribs extending between the saws and which function as virtual extensions of the huller ribs, occluding the spaces between the saws above the ribs to prevent hulls and debris from entering the roll box.

Another object of the invention is to mount the said rotary elements on an axis parallel to the axis of the saws and offset outwardly with respect to the space above the ribs, and to rotate said elements in the same direction to that of the rotation of the saws, whereby they clear the cotton from the saws by a downward wiping action.

Still another object of the invention is to provide a rake member in the huller breast adjacent the roll end of the roll box having teeth which interdigitate with the rotary elements and function to clear the cotton from between said elements, preventing its packing about the saws with consequent risk of catching fire through friction.

Other objects of the invention will appear as

the following description of a preferred and practical embodiment thereof proceeds.

Referring to the drawings which accompany and form a part of the following specification, and throughout the several figures of which the same reference characters have been employed to designate the identical parts:

Figure 1 is a side elevation, particularly in section, of a huller gin embodying the features of the present invention; and

Figure 2 is a fragmentary front elevation particularly in section.

Referring now in detail to the several figures, the numeral 1 represents the gin as a whole, comprising an inner or ginning breast 2, and an outer or huller breast 3. The upper portions of said breasts cooperate to define a roll box 4, while the lower portions of said breasts define a seed duct 5 communicating with the roll box. The saws 6 are mounted upon a shaft 7 supported by a fixed part of the gin and driven so as to rotate in the direction indicated by the arrow a.

The lower part of the ginning breast is formed with a series of parallel ribs 9 while the lower part of the huller breast is formed with a shield 10 comprising a series of short ribs 11. When the breasts are in operative position the saws intersect the seed duct passing through both sets of ribs.

It will be observed from Figure 1 that the ribs of the series 11 are relatively short, terminating at points below the rims of the saws 6 in the upper quadrant of said saws. This is in contradistinction to the conventional huller ribs which usually extend all the way up to the roll box.

It will be observed in Figure 1 that the rims of the saws 6 in the upper quadrant do not pass between the huller ribs 11, but through an unrestricted space 13 which extends clear across the gang of saws. Thus, if a long lock of cotton is engaged by adjacent saws it can be carried through into the roll box without being piled up against an intervening rib and being broken by the action of the saws. This feature as has been suggested, is of great advantage, particularly when dealing with long staple cotton.

In order to prevent hulls and other debris which are kicked about by the huller drums 14 and 15 in the huller breast from flying through the space between the saws above the ends of the ribs 11, a barrier is provided in the form of a rotary member which as a whole is designated by the reference character 16. This rotary member comprises a shaft 17 mounted in the

outer breast parallel to the axis of rotation of the saws and offset outwardly from the upper ends of the ribs 11, and a plurality of rotary elements 19 mounted on said shaft to rotate therewith. Said elements each comprise preferably a hub member 18 and a disc 19 extending radially from said hub member, said disc having the teeth or serrations 20, which serrations extend a short distance between the saws.

10 On account of the offset position of the rotary member 16, it preserves the complete lateral openness of the space 13, crosswise of the saws, while at the same time functioning as an effective baffle barrier to prevent hulls and other debris being thrown into said space.

15 The rotary member 16 has still another important function. It is suitably driven so as to rotate in a counterclockwise direction, that is to say, to rotate in the direction of rotation as the saws. This causes the interdigitating portions of the saws and serrations to be traveling in opposite directions. The peripheral speed of the serrations 20, preferably does not exceed that of the rims of the saws.

20 25 It will be understood that through centrifugal force the cotton carried by the saw teeth is accumulated along the extreme peripheral portions of the saws so that the serrations 20 function to wipe the cotton off of the saw teeth, freeing it from the saws, and permitting it to enter into the roll box past the teeth 21 of the seed guard 22.

30 35 A certain amount of the cotton thus wiped off of the saw blades will cling to the rotary elements 19. If not removed, it might become packed and overheated by frictional engagement of the saws therewith. The invention, therefore, provides the cleaning rake 23 having a series of teeth 24, which lie between the rotary elements 19 in a position to clean them of adherent cotton.

40 45 It will be understood to those skilled in the art that the specific details of construction and arrangement of parts as herein illustrated and described are by way of example and not to be construed as limiting the invention which is described in the appended claims.

What I claim as my invention is:

1. In a huller gin of the type comprising an outer huller breast cooperating with an inner ginning breast to form a roll box between their

upper portions and having ribbed lower portions forming between them a seed duct, with gin saws operating between the ribs, the ribs of the huller breast terminating below the rims of the saws in the upper quadrants of the saws forming unobstructed passages between the saws, to the roll box, a rotary member carried by the huller breast on an axis parallel to the axis of the saws, positioned outwardly of said unobstructed passages, including elements with serrations extending between the saws whose paths of rotation lap the saw rims, and a fixed member having teeth projecting between the elements having serrations, for clearing cotton from between said elements.

2. In a huller gin of the type comprising an outer huller breast cooperating with an inner ginning breast to form a roll box between their upper portions, and having ribbed lower portions forming between them a seed duct, with gin saws operating between the ribs, the ribs of the huller breast terminating below the rims of the saws in the upper quadrants of the saws forming unobstructed passages between the saws, to the roll box, a rotary member carried by the huller breast on an axis parallel to the axis of the saws, positioned outwardly of said unobstructed passages, including elements with serrations extending between the saws whose paths of rotation lap the saw rims, said rotating member being driven in the same direction as that of the saws whereby it functions to wipe cotton from the saws, and a relatively fixed member having teeth projecting between the elements having serrations, for clearing cotton from between said elements.

3. In a huller gin of the type comprising an outer huller breast cooperating with an inner ginning breast to form a roll box between their upper portions and having ribbed lower portions forming between them a seed duct, with gin saws operating between the ribs, the huller breast ribs comprising a set of stationary short ribs between the lower portions of said saws, and rotating ribs above said stationary ribs between said saws, and a fixed member having teeth projecting between said rotary ribs for clearing cotton from between said ribs.

JEFFREY J. WALLACE.
